UNITED STATES PATENT OFFICE

CLIFFORD L. KEDDY, OF LYNN, MASSACHUSETTS

ROUNDABOUT

Application filed January 7, 1929. Serial No. 330,949.

My invention relates to amusement apparatus, particularly roundabouts or merry-go-rounds, and it has for its object to provide an improved apparatus of this class.

5 Roundabouts are constructed with a passenger-carrying element or rotor structure that is actuated to convey or move the passengers in a circular path around the axis thereof, but in all of the constructions here-
10 tofore proposed, so far as I am aware, the only motion imparted to this passenger-carrying element as a whole has been the rotary motion referred to.

My invention provides a roundabout 15 amusement apparatus wherein the passenger-carrying structure is rotated as with the apparatus heretofore proposed, but which is so constructed and operated that said rotor structure can be, or is, also raised and lowered, and this is a distinguishing and characterizing feature of my invention in whatever form it may be embodied.

In the accompanying drawings:

25 Figure 1 is an elevation, partly in section, of a roundabout constructed in accordance with my invention.

Figure 2 is a section on line 2—2 of Fig. 1.

30 Figure 3 illustrates another structure embodying my invention.

The form of my invention shown in Figs. 1 and 2 comprises a vertically disposed cylinder 10 the lower portion of which is buried in the ground G and the lower end of which 35 is bolted to a flanged head 11 seated upon a concrete foundation 12 to which it may be anchored in any suitable fashion.

This cylinder 10 occupies a position at the 40 middle of a circular bowl 13 built up from concrete and formed at its middle with an elevation or pedestal 14 that serves as a support for a platform 15. The platform 15 is made upon its top side with a circular runway 45 for a series of conical rollers 16 on which rests a flange 17 provided at the lower end of a sleeve 18 surrounding the upper portion of cylinder 10 and journaled near its upper and lower ends on bearings provided upon 50 the exterior of the latter, said flange being

provided upon its under side with a runway for said rolls 16.

The bowl 13 is filled with a body of water W and the pedestal 14 supports the platform 15 and parts carried by it above the level 55 of said water W.

The flange 17 is made with a circular rack of gear teeth 19 engaged by a beveled pinion 20 that is compounded with a relatively large spur gear 21 driven by a small pinion 60 22 fast on the armature shaft of an electric motor 23, said motor being mounted upon a stand 24 which, in turn, is mounted on the platform 15.

Within the cylinder 10 is a piston 25 having 65 a stem 26 extending upwardly from its top end to a point well above the upper end of the sleeve 18 where it has mounted upon it a collar 27 to which are connected the inner ends of a plurality of stays 28. At its outer end each stay 28 is fastened to the outer end of a radially disposed rigid arm 29, and the inner ends of all of these arms are securely fastened to a collar 30 mounted upon the stem 26 in a position above sleeve 18 and pinned 70 or otherwise rigidly fixed to said stem.

The stem 26 is, as shown in Fig. 2, made exteriorly hexagonal in shape and extends loosely through a correspondingly shaped hole provided at the upper end of sleeve 18, 80 so that the rotary motion imparted to sleeve 18 will be transmitted to the stem 26 and at the same time the latter is free to move up and down within the hexagonal hole of the sleeve. 85

The lower end of the cylinder 10 is connected by a conduit 31 with the outlet 32 of a pump 33 whose inlet 34 has connected with it one end of the conduit 35 whose opposite end is submerged in the body of water W 90 within bowl 13. At a predetermined distance above the lower end thereof the cylinder 10 is made with an outlet with which is connected one end of a conduit 36 that discharges at its opposite end into bowl 13. 95

The pump 33 is driven by an electric motor 37 mounted upon platform 15, and it will be clear that when said motor and pump are in action, water is pumped from bowl 13 through conduit 35; pump 33 and conduit 31 100

into the cylinder 10 at the lower end thereof, thus forcing the piston 25 and stem 26 upwardly, and it will also be clear that upward movement of the piston and stem will be arrested automatically as soon as the piston, in moving upward, uncovers the outlet with which the conduit 36 is connected. When this occurs the water thereafter is discharged from the cylinder through conduit 36 as fast as it is delivered into the cylinder by pump 33, the piston remaining stationary, so far as endwise movement is concerned, at the limit of its upward movement. It will also be clear that the piston will remain supported in this elevated position by the water even though the pump 33 be stopped.

Connected at its opposite ends with the conduits 31 and 35, respectively, is a by-pass conduit in which is arranged a normally closed valve 39, and when it is desired to lower the piston 25 from its elevated position, pump 33 being at rest, the valve 39 is manually opened by means of its handle, whereupon the weight of the piston and parts carried by it lowers the same, the water in front, or below, the piston being forced from cylinder 10 through conduit 31, by-pass 38 and conduit 35 back into the bowl 13. By means of valve 39 the speed of downward movement of piston 25 may be regulated thereby timing its descent as may be desired.

The upper ends of a plurality of cables 40 are attached to the outer ends of the arms, two to each arm, and there are a number of pairs of these cables whereof the lower ends of each pair are fastened to the opposite ends of a boat 41 which may be supported by the water W when the piston and its stem are at the limit of their downward movement. Upon the inside of each of these boats may be provided seats, not shown, for the passengers.

While the apparatus is at rest and the boats 41 are in their lowermost positions, the passengers are loaded into the same from the embankment 42 at the outside of the bowl 13, and when loaded the motor 23 is started and operates through the pinion 22, gear 21 and pinion 20 to rotate sleeve 18 which transmits its rotary motion to the stem 26 and parts carried thereby, thus moving the boats through the water in a circular path. Then, at any time after the rotor of the apparatus is in motion, pump 33 may be started, whereupon the rotor with its boats is raised to the limit of the movement of piston 25, or to any other desired height under said limit. Or the motor 37 which drives the pump 33 may be started first and thereafter the motor 23.

It will be noted that the piston is supported in its elevated position by a fluid bearing so that very little frictional resistance is offered thereby to its rotation.

Heretofore, roundabouts having pendant

carriages for the passengers have been so constructed that said carriages were permanently maintained in positions well elevated above the ground, and therefor it has been necessary to provide in connection therewith a correspondingly elevated stationary platform leading to the same, for use in loading and unloading the passengers. My invention dispenses with the platform and stairway heretofore required; it provides an apparatus which can be loaded and unloaded with rapidity; it combines travel on a pond with flight through the air, and the variety of movements imparted to the rotor makes my apparatus more attractive to patrons than this heretofore provided.

As shown in Fig. 3, the bowl 13 may be dispensed with and the platform 15 arranged upon the same level as the ground G. With this form of my invention I may provide a tank 43 holding a supply of water with which the outlet of cylinder 10 is connected by a return conduit 36a, while the supply conduit 35 is extended downwardly into said tank to supply water to the pump.

My invention is not limited to the particular means herein shown for supplying fluid under pressure to the cylinder 10 to raise piston 25, and any other suitable means may be substituted. Also, the upper portion of the rotor of the apparatus by which the passengers are carried may be modified as desired.

What I claim is:

1. An amusement apparatus of the character described having, in combination, a passenger-carrying rotor element provided at its middle with a vertical stem having a piston adjacent its lower end; a stationarily supported vertically disposed cylinder within which said piston is arranged, said cylinder being closed at its lower end and provided with an inlet port adjacent said closed lower end and with an outlet port intermediate its opposite ends that is positioned a predetermined distance above said inlet port; a power operated pump having its outlet connected with the inlet of said cylinder, and means for turning said rotor element.

2. An amusement apparatus of the character described having, in combination, a passenger-carrying rotor element provided at its middle with a vertical stem having a piston adjacent its lower end; a stationarily supported vertically disposed cylinder within which said piston is arranged, said cylinder being closed at its lower end and provided with an inlet port adjacent said closed lower end and with an outlet port intermediate its opposite ends that is positioned a predetermined distance above said inlet port; a power operated pump having its outlet connected with the inlet of said cylinder; a reservoir with which the inlet of said pump and the outlet of said cylinder are connected, and means for turning said rotor element.

3. An amusement apparatus of the character described constructed in accordance with claim 1 wherein the rotor element is equipped with pendant boats and wherein said reservoir is an artificial lake surrounding said cylinder on which said boats rest when said rotor element occupies its lowermost position.
- 5 4. An amusement apparatus of the character described constructed in accordance with claim 2 wherein there is also provided a by-pass extending around said pump one end of which communicates with the outlet of said pump and the other end of which communicates with the inlet of said pump, and a valve in said by-pass operable to effect upward and downward movement of said piston.

10 5. An amusement apparatus of the character described having, in combination, a passenger-carrying rotor element provided at its 20 middle with a vertical stem having a piston at its lower end; a cylinder supported in a vertical position and within which said piston is arranged; means for rotating said element; means for supplying fluid under pressure to said cylinder adjacent its lower end to raise said piston and said element; means for exhausting said fluid from said cylinder to lower said piston and element, said cylinder being made with an outlet port that is uncovered by the piston during its upward movement to stop said upward movement when the piston reaches a predetermined height.

25 Signed by me at Boston, Suffolk County,
30 Massachusetts, this 4th day of January, 1929.
35 CLIFFORD L. KEDDY.
